UNITED STATES PATENT OFFICE.

EDGAR FRANKLYN BENGERT, OF KANSAS CITY, MISSOURI.

DESIGN FOR A RING.

Application filed May 25, 1925. Serial No. 13,562. Term of patent $3\frac{1}{2}$ years.

To all whom it may concern:

Be it known that I, EDGAR FRANKLYN BENGERT, a citizen of the United States, residing at Kansas City, in the county of Jackson and State of Missouri, have invented a new, original, and ornamental Design for a Ring, of which the following is a specification, reference being had to the accompanying drawing, forming a part hereof.

Figure 1 is a top plan view of a ring showing my new design.

Figure 2 is a side view thereof.

What I claim is:

The ornamental design for a ring, as shown.

EDGAR FRANKLYN BENGERT.
